(57) **CLAIM**

The ornamental design for a personal digital terminal, as shown and described.

DESCRIPTION

FIG. 1 is a perspective view showing our new design for a personal digital terminal;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines shown in FIGS. 1-8 illustrate portions of the personal digital terminal that form no part of the claimed design.
